INTERMITTER VALVE FOR PRODUCING OIL
WELLS

Athelstan T. Watson, Cabimas, Zulia, Venezuela

Application August 24, 1938, Serial No. 226,605

1 Claim. (Cl. 137—145)

This invention relates to an intermitter valve for installation in a high pressure gas or air lift line associated with producing oil wells and it consists in the constructions, arrangements and combinations herein described and claimed.

It is an object of the invention to provide an intermitter valve embodying automatic controlled timing to evacuate fluid through the macaroni string as fast as the string fills up with fluid.

10 It is also an object of the invention to provide novel arrangements of valves whereby the intermittency of operation may be regulated according to flow of oil in the well.

It is a still further object of the invention to provide 15 an intermitter valve of extreme simplicity, enabling construction at a low cost; one which employs a minimum of gas in operation, and one which is free from troubles arising from sand intermingling with the fluid elevated.

20 Additional objects, advantages and features of invention will be apparent from the following description and accompanying drawing, wherein—

Figure 1 is a plan view of the intermitter valve installed in a high pressure gas line.

25 Figure 2 is an enlarged cross section taken on the line 2—2 of Figure 1.

Figure 3 is a plan view of a back pressure valve guide.

Attention is first invited to Figure 1 wherein 30 there is shown a high gas pressure line 10 connected to a suitable conduit 11 by an extension line 12. A suitable valve 13 is interposed between the lines 10 and 12 for a purpose presently to be explained. The line 10 includes a by-pass line 35 14 which has installed therein a valve 15, whereby flow of gas to a container 16 may be controlled.

The oil or other well is represented at 17 and includes a macaroni string generally indicated at 18. A pipe line 19 in communication with the 40 header 11a opens into the macaroni string for admission of gas thereto. An oil and gas discharge line 20 is suitably connected to the well and will conduct the oil and gas to a suitable separator (not shown) for recovery of the gas.

45 As clearly shown in Figure 2, the intermitter valve 21 is connected to the header 11a, and in order that this connection may be made, the intermitter valve comprises a straight, flanged pipe section 22 complementary to a flanged port 23 of the header; and an elbow portion 24, flanged as at 25, for connection with a flanged port 26 of the conduit 11.

The intermitter valve includes a tubing 27 one end of which is connected to the elbow 24, the 55 other end having a back-pressure valve housing

28 connected thereto. At a suitable point in the tubing 27 there is an upstanding cylinder 29, extending transversely through the tube and closed at its lower end by a valve cage 30, the upper end of which is faced to provide a valve seat 31. 5 The cage 30 also has a port 32 adapted to register with a port 33 of the cylinder 29, these ports being in communication with the elbow 24, at all times. The cylinder 29 also includes a port 33a positioned above the valve 37, opening upon the 10 high pressure chamber 27a of the conduit 27.

Within the cylinder 29 there is reciprocably mounted a triple valve 34. The valve 34 comprises a stem 35 guided by a block 36, the lower end of the stem having a poppet valve 37 complementary to the seat 31 and yieldingly held thereto by a helical spring 38 interposed between the valve and the block 36. The stem 35 also has a piston 39, positioned upon the upper side of the guide 36 and a valve block 40 rigidly secured in the cylinder 29 has a bore faced to receive a valve 41, this valve being rigid, with the stem and held thereto by the tension of the spring 38. A second valve block 42 is fixed in the cylinder 29 and comprises a downwardly opening valve 25 face 43 complementary to a valve 44 fixed to the upper end of the stem 35, the valve being held in open position until closed by actuation of the stem 35. The valve block 42 includes a vent 45 opening into a dome 46 fixed to the upper end of 30 the cylinder.

The valve blocks 40 and 42 each include a port 47—48 respectively permitting passage of gas therethrough, as will be apparent as the description proceeds.

35 In the present instance the valve blocks 40 and 42 are shown as integrally connected by a sleeve 40a, the latter being secured within the cylinder by a screw plug 40b. The threaded end of the valve fitting 56 also engages in the sleeve. By 40 this construction the assembly may be readily removed for refacing of the valve faces, cleaning and otherwise.

The cylinder 29 has a threaded nipple 49 for 45 securement of a valve cage 50, which adjustably mounts a needle valve 51 for regulating flow of gas through ports 52, 53 and 54. The port 52 is in communication with a pipe 55 opening upon the tubing 27 in advance of the elbow 24, while the 50 port 54 opens immediately below the valve 41.

A valve cage 56 is threaded engaged with the cylinder 29 and the valve block 42, and comprises a port 57 in communication with a port 58 of the valve block 42. A needle 59 regulates the pres- 55

sure of gas within the dome by regulating passage of gas to the atmosphere through vent 60.

The back-pressure valve housing 28 comprises oppositely disposed valve seats 61—62 immediately above the pipe section 22, and reciprocably mounted between these seats, for alternate seating engagement therewith, is a double-faced valve 63. The valve cage 64 which carries the valve seat 62 has a slide bearing support 65 for the rod 66 of the valve. The rod 66 has rigidly secured to its end a piston 67. The outer end of the housing 28 is interiorly screw-threaded and receives an adjusting plug 68, for varying the tension of a helical spring 69 interposed between the piston 67 and the plug. By adjusting the tension of the spring the opening movement of the valve 63 may be regulated. The housing 28 also includes a vent dome 70 opening upon the space between the piston 67 and the cage 64.

20

The operation

The operation will be readily understood from the following description.

Gas under high pressure is admitted by way of the pipe line 10, the valve 13 being closed, the gas passes through valve 15, pipe 14 into the receiver 16 and thence through elbow fittings 24. A portion of the gas will pass through ports 52, 53 and 54, this being determined by the setting of the needle valve 51. Gas will also be admitted through the ports 33—32 beneath the valve 37 until pressure has built up to overcome the tension of the spring 38. When such pressure has developed, the valve 37 will be raised to permit passage of gas into the high pressure chamber 27 by way of the port 33a. When the valve 37 is raised, the valve 41 is also raised, permitting passage of gas through the ports 52, 53 and 54 into the dome 46 by reason of the port 48. When the valve 37 has been fully opened the valve 44 will have been moved to closed position. The pressure of gas will continue to build up in the dome and influence of this pressure by reason of the port 47 will tend to force the piston 39 downwardly to seat the valve 37, and such seating of the valve 37 does occur when the required pressure has built up in the dome 46 and the upper portion of the cylinder 29 above the piston 39.

In the meantime, pressure has built up in the chamber 27a to such extent that the valve 63 has been moved to engage the seat 62 of the cage 64, moving the piston 67 rearwardly against the spring 69. Thus, the gas released from the chamber 27a passes into the header 11a and conduit 19 and into the macaroni string 18 for elevation of the fluid in the well. As soon as the

pressure in the dome 46 has been built up, the valve 37 is immediately seated, preventing further entrance of gas into the chamber 27a. At such time, the spring 69 urges the valve 63 into engagement with the seat 61, but which does not occur until the pressure in the macaroni string is reduced to the equivalent of the spring tension 69 and in this position of the parts, the intermitter valve will be again actuated as soon as pressure has reduced in the dome 46, and thus an intermittent flow of gas to a well is effected.

In the event that continuous flow of gas to the well is desired, the valve 15 is closed and the valve 13 opened. It will be apparent that gas will now flow through the pipe 12, the header 11a, the pipe 15 into the well 18.

While I have shown and described a preferred form of the intermitter valve, this is by way of illustration only, and I consider as my own, all such modifications in structure as fairly fall within the scope of the appended claim.

I claim:

An intermitter valve for gas lift wells comprising a conduit having means at one end for connection with a high pressure gas line, means adjacent the other end for connection with a well, an upright, closed cylinder carried by the conduit, extending therethrough and dividing the conduit defining a high pressure chamber, a valve cage in the base of the cylinder, and having an upwardly disposed valve seat, a valve complemental to the seat, said valve having a stem extended upwardly through the cylinder, a guide in the cylinder and receiving the stem therethrough, a helical spring on the stem interposed between the valve and the guide, a piston on the stem above the guide, lower and upper valve blocks in the cylinder each having a valve seat, valves on the stem complemental to each seat, the uppermost valve being in open position at the time the first named valve is in seated position, each of the valve blocks having ports to admit gas above the piston, the lowermost valve block having a gas port controlled by the valve thereof, a by-pass conduit connected with the gas inlet conduit and said port, a needle valve controlling passage of gas through the by-pass and the port, said upper valve block having ports open to the atmosphere, a needle valve for regulating passage of gas through the ports, a port in the cylinder below the first named valve establishing communication with the gas inlet, and a port in the cylinder above the first named valve establishing communication with the high pressure chamber.

ATHELSTAN T. WATSON.
